UNITED STATES PATENT OFFICE.

ARTHUR M. O'QUINN, OF MIAMI, FLORIDA.

SIZER AND GRADER.

1,379,207.

Specification of Letters Patent. Patented May 24, 1921.

Application filed July 30, 1920. Serial No. 400,089.

To all whom it may concern:

Be it known that I, ARTHUR M. O'QUINN, a citizen of the United States, residing at Miami, in the county of Dade and State of Florida, have invented a new and useful Sizer and Grader, (Case C,) of which the following is a specification.

The machine forming the subject matter of this application is adapted to be employed for grading fruit, vegetables and other articles, one object of the invention being to simplify the mounting of the members whereby the sizing operation is accomplished. Another object of the invention is so to construct the machine that the material to be sized will be fed positively to the members whereby the sizing operation is brought about. A further object of the invention is to reduce the number of parts and to strengthen the machine.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in vertical longitudinal section a machine constructed in accordance with the invention; Fig. 2 is a transverse section; Fig. 3 is a fragmental top plan showing a portion of one of the conveyer chains and the links which carry the grading or sizing members; Fig. 4 is a sectional detail taken through one of the sizing rollers and attendant parts, certain elements appearing in elevation; Fig. 5 is a top plan of the complete machine.

In carrying out the invention there is a frame 1 which may be constructed in various ways without jeopardizing the utility of the device hereinafter described and claimed. The frame 1 may include upper supports 2, which may be angle members. The frame 1 embodies a lower support 3. Above the support 3 are located oppositely

inclined deflectors 4, shown in Fig. 2, the deflectors discharging upon packing tables 5, as is common and well understood in the art.

A drive shaft 6 is supported for rotation on one end of the frame 1, a shaft 7 being supported for rotation on the opposite end of the frame, the frame carrying an intermediate shaft 8, located between the shafts 7 and 6, and relatively near to the shaft 6. There are sprocket wheels 9 on the shaft 7, the shaft 6 being supplied with sprocket wheels 11, the shaft 8 having sprocket wheels 10. Drums 12 are mounted on the shaft 7, similar drums 14 being carried by the shaft 6. An inclined table 15 is mounted on the frame 1 and extends from a point adjacent to the sprocket wheels 9, over and in front of the intermediate shaft 8.

The machine includes a conveyer comprising chains 16 engaged around the sprocket wheels 9 and 11. The upper runs of the sprocket chains 16 move along the upper supports 2, the lower runs of the chains 16, and parts carried thereby, moving along the lower support 3. The chains 16 coöperate with the sprocket wheels 10 on the intermediate shaft 8 and it is to be observed that, owing to the provision of the sprocket wheels 10, portions of the chains 16, and parts carried thereby are supported while the chains are moving forwardly along the table 15.

Certain of the links of the chains 16 are provided with inwardly extended projections or pins 17 mounted in the ends of a tube 18. The tube 18 forms a pivotal mounting for the inner ends of links 19, the links 19 being disposed in pairs and being mounted to swing in vertical planes. The links 19 are prevented from moving longitudinally of the tube 18 by collars 20 on the tube, these collars being disclosed clearly in Fig. 3.

In the outer ends of the links 19 there are openings 21 facilitating the mounting of rollers 22, the rollers constituting sizing members, as will be evident from what is stated hereinafter. The links 19 are provided with inwardly extended flanges 23 having openings 24 adapted to receive screws 25 or other attaching elements, retaining fillers 26 on the respective links 19, the fillers extending from the links at one side of the machine to the links at the other

side of the machine. The fillers 26 may be concaved or cut away, as indicated at 75, so as to overhang and coöperate with the sizing members 22 (see Fig. 4).

5 The machine includes a track made up of rails 27, the terminal rails of the track being designated by the numeral 36, the terminal rails 36 resting on the drum 14 of the shaft 6, as shown in Fig. 1. The ends of the 10 several track rails are pivotally mounted on supports 28, which may be rods. Vertical screws 29 are provided, the lower ends of the screws 29 being mounted for rotation in the ends of the supports 28, as shown at 30. The 15 screws 29 are mounted to rotate in brackets 31 carried by the frame 1, the screws being threaded into worm wheels 32 supported on the brackets. Transverse shafts 33 are journaled on the brackets 31 and are sup- 20 plied with worms 34 meshing into the worm wheels 32, each shaft being provided, at one end, with a squared extremity 35, adapted to receive a wrench or key (not shown) whereby rotation may be imparted to the 25 shaft.

In practical operation, the conveyer chains 16 are advanced in the direction of the arrow A in Fig. 1, through the instrumentality of the drive shaft 6 and its sprocket 30 wheels 11. At the right hand end of the machine (Fig. 1), the links 19 are disposed in substantial alinement, the fillers 26 being alined, and the sizing members 22 moving along the table 15. The fruit or other ma- 35 terial to be sized is delivered into the machine at the right hand end thereof. (Fig. 1). While the rollers or sizing members 22 are traversing the table 15, the fruit is distributed between the sizing members 22 of 40 adjacent pairs, and is arranged in lines ex- tended transversely of the machine. Conse- quently, before the sizing operation actually begins, the material is distributed and ar- ranged in such a way that there will be no 45 choking or crowding when the sizing opera- tion is begun. Noting Fig. 4, it will be ob- served that the inner edges of the parts 26 abut, as indicated at 76, when the links 19 are in alinement. Consequently, when the 50 sizing members 22 are moving along the table 15, the parts 26 are maintained in par- allel relation to the table, and cannot sag downwardly. The distribution of the fruit or other material to the sizing members 22 55 is promoted, by the construction and the operation last above alluded to.

Rotation may be imparted to the shafts 33, the worms 34 driving the worm wheels 32. When the worm wheels 32 are rotated, 60 the screws 29 will be raised and lowered, because the screws are threaded into the worm wheels. The supports 28 will be raised or lowered, along with the screws, and, since the supports carry, pivotally, the 65 ends of the track rails 27, the track rails may

be spaced at different distances, vertically, from the plane in which upper runs of the conveyer move.

The sizing members 22, leaving the table 15, pass upon and traverse the track rails 27, one after another, the links 19 swinging downwardly on the members 18, to permit the rollers or sizing elements 22 to coöperate with the track rails. An inspection of Fig. 1 will render it evident that as the sizing 75 members 22 approach the left hand end of the machine, the sizing members of adjacent pairs will be spaced apart more widely than at the right hand end of the machine, since the track rails 27 at the left hand end of the 80 machine are lower than the track rails at the right hand end of the machine. Consequently, the fruit or other material of smaller size will drop downwardly adja- 85 cent to the right hand end of the machine, the fruit being graded according to size, as the fruit is advanced toward the left end of the machine. The fruit, having been graded, is received by the deflectors 4 and carried upon the packing tables 5. 90

It is to be observed that one end roller 22 of each pair is thrust along the track 27, by the action of the conveyer whereas, the other roller of each pair is dragged along the track by the action of the conveyer. 95 This operation reduced the strain on the machine materially. The rollers 22 between which the sizing operation takes place, are in approximately the same plane with re- 100 spect to the horizontal. Owing to the con- struction above alluded to, and owing to the further fact that the fillers 26 converge downwardly toward the rollers which are effecting the sizing operation, there is an even distribution of the material to be sized, 105 and a positive feed of the material to the sizing rollers.

The tube 18 constitutes merely an element whereon the inner ends of the links 19 are mounted pivotally, and especial attention is 110 directed to the fact that the tube 18 has ab- solutely nothing whatever to do with the sizing operation, the sizing taking place be- 115 tween the rollers 22 of adjoining pairs, an obser- vation which will be understood clearly when Fig. 1 of the drawings is noted. As the conveyer is advanced, the links 19 are moved, by the action of the table 15 and the track elements 27, from a position in 120 which the links are in approximate aline- ment, to a position in which the links of each pair are disposed at an angle to each other, thereby to regulate the sizing space which exists between the rollers 22 on the links of adjoining pairs. 125

Having thus described the invention, what is claimed is:—

1. In a sizer and grader, a frame; a con- 130 veyer traversing the frame; members be- tween which the material is sized; means

for suspending said members from the conveyer for up and down swinging movement; a track along which said members move; and means for adjusting the track to vary 5 the sizing space between said members.

2. In a sizer and grader, a frame; a conveyer mounted on the frame; a track, means for adjusting the track vertically; sizing members disposed in pairs and traversing 10 the track; means for connecting one sizing member of each pair to the conveyer and for imparting a thrust along the track from the conveyer to said member; and means for connecting the other sizing member of each 15 pair to the conveyer and for imparting a drag along the track from the conveyer to said member.

3. A sizer and grader comprising members between which the material is sized; a conveyer; means for mounting said members on the conveyer for swinging movement toward and away from each other in the arcs of circles; and means for limiting the swinging movement of said members, thereby to regulate 25 the sizing space therebetween.

4. A sizer and grader embodying a conveyer; links having a common pivotal mounting on the conveyer; sizing members carried by the outer ends of the links and 30 mounted to swing with the links, thereby to vary the sizing space between said members; and means for adjusting and regulat-

ing the swinging movement of the links and of said members.

5. A sizer and grader embodying a conveyer; links having their inner ends pivoted to the conveyer; sizing members carried by the outer ends of the links and mounted to swing with the links; fillers mounted on the links and bridging the space between the 40 sizing members; and mechanism for regulating the swinging movement of the links when the links are advanced by the conveyer.

6. A sizer and grader comprising a conveyer; pairs of links pivoted at their inner 45 ends to the conveyer; members at the outer ends of the links, the members of the links of adjoining pairs coacting to effect a sizing of the material; and means effective when the conveyer is advanced, for moving the 50 links of each pair progressively from a position of approximate longitudinal alinement to a position in which the links of each pair are at an angle to each other, thereby to adjust the sizing space between said members on the links of adjoining pairs.

In testimony that I claim the foregoing as my own, I have hereto affixed my signature in the presence of two witnesses.

ARTHUR M. O'QUINN.
